(57) **CLAIM**

The ornamental design for a lighting apparatus, as shown and described.

DESCRIPTION

FIG. 1 is a top perspective view of a lighting apparatus of the present invention;

FIG. 2 is a front view thereof, the rear view being a mirror image thereof;

FIG. 3 is a left side view thereof, the right side view being a mirror image thereof;

FIG. 4 is a top view thereof; and,

FIG. 5 is a bottom view thereof.

An elongated elevation with triangular ridges thereon is transparent and thus light comes through. The two squares are electrodes.
